UNITED STATES PATENT OFFICE.

HENRY F. SMITH, OF PHILADELPHIA, PENNSYLVANIA.

HALTER OR BRIDLE.

SPECIFICATION forming part of Letters Patent No. 258,325, dated May 23, 1882.

Application filed April 10, 1882. (No model.)

To all whom it may concern:

Be it known that I, HENRY F. SMITH, a citizen of the United States, residing at Philadelphia, in the county of Philadelphia and State of Pennsylvania, have invented certain new and useful Improvements in Halters or Bridles, of which the following is a specification, reference being had therein to the accompanying drawings, wherein—

10 Figure 1 is a perspective of a halter embodying my invention. Figs. 2, 3, 4, and 5 are perspectives of the various buckles used to unite the straps of the halter. Fig. 6 is a longitudinal vertical section of buckle H and straps. Fig. 7 is an elevation of same, and Fig. 8 is an elevation of a bridle embodying my improvements.

15 My invention has for its object to provide a bridle or halter the various component parts 20 of which (save the brow-piece) are put together so as to dispense with stitching, riveting, or other similar ways of fastening, thereby producing a cheaper and superior article than has heretofore been made.

25 My invention consists of the novel combination, construction, and arrangement of the parts forming the halter or bridle.

Referring to the accompanying drawings, A represents a halter composed of chin-and-nose 30 strap B, cheek-straps C C', and neck-strap D; and E, E', F, G, and H are buckles for securing said parts together.

35 The buckles E E' are more plainly shown in Fig. 4, and consist of the ring part e, through which passes the chin-and-nose strap B, and the rectangular part e', in which are inserted the cheek-straps C C'. The part e' is formed with a curved or straight cross-bar, e²; and e³ is a depressed bar provided with one or more studs, 40 e⁴ e⁵, and a lug, e⁶. The ring part e is formed with an eye, e⁶, for attachment of the bit to form a bridle, as shown at y, Fig. 8, and has a depressed cross-bar, e⁷, provided with one or more studs, e⁸, and an enlarged projecting lip, 45 e⁹, coinciding with cross-bar e², to form a groove or recess, e¹⁰, for receiving the end of a strap and preventing it from curving by friction.

50 The buckle F is more fully shown in Fig. 3, and consists of two parts, f f', the latter being located at an angle to the former, as indicated. The part f' is formed with cross-bar f², de-

pressed bar f³, having stud or studs f⁴, and lug f⁵. The part f is formed with cross-bar f⁶, having stud or studs f⁷, and a lip, f⁸, which forms a groove or recess, f⁹, for the insertion 55 and protection of the end of the neck-strap.

The buckle G (plainly illustrated in Fig. 2) is composed of two parts or uniting frames, g g', placed at an angle with each other. In the part g' is inserted the remaining end of neck-strap D, and is formed with cross-bar g², de- 60 pressed bar g³, having stud or studs g⁴, and lug g⁵. The part g is provided with depressed bar g⁶, having lip g⁷, which forms a groove, g¹², for the insertion of said end of the neck-strap, and in addition thereto said part g is provided with another depressed bar, g¹⁰, carrying stud or studs g¹¹ and an elevated cross-bar, g⁹, which is located between said bars g⁶ and g¹⁰, as shown, the bar g⁶ also having a tongue, g⁸. 70

The buckle H, which is separately illustrated in Fig. 5, consists of but one part or frame, h, corresponding to part g of buckle G, and is formed with depressed cross-bars h¹ h², the former carrying a swinging tongue, h³, and the latter a stud or studs, h⁴; and h⁵ is an elevated cross-bar forming part of frame h, and is situated between the cross-bars h¹ and h². 75

The halter or bridle is constructed, or its parts put together, in substantially the following manner: The near or left side cheek-strap, C, engages at its lower end with the nose-buckle E', said end entering into the recess or groove e¹⁰, and held in place by stud e⁴ of said buckle, as shown in Fig. 1. The upper end of said strap C is provided with a slot, so as to engage the tongue g⁸ of buckle G, and it encircles the bar g⁶, and the chape, or end C' thereof, passes under the elevated bar g⁹, as illustrated at x, Fig. 6, for the strap B. 90

The off or right cheek-strap, C', is one continuous strap, forming the head-band C⁴ and billet C², having holes c³ to engage with the cheek-buckle G on the left or near side. The lower end of the strap C' engages the nose-and-chin buckle E in the same manner as above described for strap C on the opposite or near side. At a suitable distance from the lower end of strap C' a hole or holes, c', are punched for engagement with the stud or studs f⁷ of buckle F. 95

The nose-and-chin band B is one continuous

strap, one end of which is slotted to engage with tongue h^3 of buckle H, as more plainly shown in Figs. 6 and 7. The other end forms the billet H' for buckle H. Said strap passes 5 through a ring, k, of hitching-tug K, thence through nose-buckles E E', and engages with their respective studs e^8 , and thence to the chin-buckle H, as illustrated.

The neck-strap D is passed through the slit 10 k' of tug K. The ends d d² of said strap are provided with openings d' d³, and engage with the studs g⁴ f⁴ and enter the grooves or recesses g¹² f⁹, respectively, of the cheek-buckles G F, in like manner as described for cheek-straps 15 on the nose-buckles E E'.

It will be noticed from the foregoing that all the parts described are put together without the aid of stitching, riveting, or other similar fastening devices.

20 The lugs g⁵, f⁵, and e⁵ are provided for giving greater bearing-surfaces for the straps at their points of connection with the buckles on which said lugs are respectively formed; but said lugs may, if desired, be dispensed with.

25 The halter A is provided with the usual brow-piece, I, and hitching-tug K. The latter may be a metal tug of any desired shape or construction; or the usual leather tug may be employed.

30 If desired, a strap, L, may be used for re-enforcing the chin-strap, and thereby make such part of the holder or bridle more durable than would otherwise be the case if but a single strap were used. Said strap L is secured at one 35 end, l, to stud e⁸ of buckle E, and at its opposite end, l', to stud h⁴ of buckle H, as more plainly shown in Fig. 6.

Fig. 8 shows a bridle embodying my invention, wherein the chin-and-nose strap B and 40 cheek-straps C C' are arranged and secured together by buckles E E' and H, as above set forth; but the neck-strap is secured to or passes through loops in brow-piece I, as shown. In such case the buckles F and G are dispensed 45 with, and in lieu of buckle G a buckle, H, is substituted, and a double band or strap, M, is provided.

The grooves or recesses e¹⁰, f⁹, and g¹² are respectively formed in buckles E, F, and G for

receiving and protecting the ends of the cheek 50 and neck straps, as shown, and the elevated bars g⁸ and h⁵, respectively, of buckles G and H are provided in order that the chape ends of straps C and B may be tucked under said bars without requiring said ends to be shaved or reduced in thickness. 55

I am aware that two-part buckles with bars and studs have been employed to connect the various straps of halters and bridles. Therefore I do not claim such buckles, broadly, but only 60 when they are provided with grooves or recesses e¹⁰, f⁹, and g¹², as above described.

What I claim as my invention is—

1. The improved halter or bridle, having continuous cheek-and-head strap C' C⁴ and a 65 separate cheek-strap, C, united to strap C' by a tongued buckle, the two-part buckles E E', having grooves or recesses e¹⁰ for the reception and protection of the lower ends of cheek- 70 straps C' C', and the continuous nose-and-chin strap B, secured to buckles E E', and provided with a tongued buckle, said parts being constructed substantially as shown and described.

2. A halter-buckle composed of two uniting frames or parts formed with a depressed cross-bar having a projecting lip adapted and designed to form a recess or groove for the reception and protection of the end of a strap, 75 substantially as shown and described.

3. The combination, with cheek-straps C C' 80 and chin-and-nose strap B, united by buckles E E', formed with grooves or recesses e¹⁰, constructed substantially as shown and described, of the re-enforcing strap L, secured at one end to buckle E and at its opposite end to a buckle, 85 H, on strap B, substantially as shown and described.

4. The buckle H, having depressed cross-bars h' h² and intermediate bar, h⁵, elevated above frame h, the bar h' carrying tongue h³ 90 and the bar h² formed with or without stud h⁴, substantially as shown and described.

In testimony whereof I affix my signature in presence of two witnesses.

HENRY F. SMITH.
